UNITED STATES PATENT OFFICE

144,725

DESIGN FOR A COMBINED AUTOMOBILE WHEEL COVER AND HUB CAP OR SIMILAR ARTICLE

George Albert Lyon, Allenhurst, N. J.

Application July 7, 1945, Serial No. 120,552

Term of patent 14 years

(Cl. D14—30)

To all whom it may concern:

Be it known that I, George Albert Lyon, a citizen of the United States, and a resident of the village of Allenhurst, in the county of Monmouth and State of New Jersey, have invented a new, original, and ornamental Design for a Combined Automobile Wheel Cover and Hub Cap, or Similar Article, of which the following is a specification, reference being had to the accompanying drawing, forming a part thereof.

On the drawing:

Figure 1 is a side view of a combined automobile wheel cover and hub cap embodying my new design;

Figure 2 is a profile view of a diametric section taken through Figure 1;

Figure 3 is an enlarged fragmentary cross-sectional view.

The dotted line showing of a conventional tire and wheel in Figures 1 and 2 is for illustrative purposes only.

I claim:

The ornamental design for a combined automobile wheel cover and hub cap or similar article, as shown and described.

GEORGE ALBERT LYON.
